UNITED STATES PATENT OFFICE.

FREDERIC ECAUBERT, OF BROOKLYN, NEW YORK.

DESIGN FOR A METAL RING.

SPECIFICATION forming part of Design No. 23,684, dated October 9, 1894.

Application filed June 29, 1894. Serial No. 516,121. Term of patent 14 years.

To all whom it may concern:

Be it known that I, FREDERIC ECAUBERT, a citizen of the United States, residing at Brooklyn, in the county of Kings and State 5 of New York, have invented a new Design for a Metal Ring, of which the following is a specification.

This design applies to the exterior surface of a metal ring such as used in watch case 10 centers, lockets, napkin rings, &c.

The leading feature of my design consists in the beveled sides and concave scalloped edge with a convex ornament.

In the drawings, Figure 1. is a side view

representing the ornament. Fig. 2. is an edge 15 view, and Fig. 3. is a cross-section of the ring at one side. These views are in large size.

The sides of the ring are beveled and the edges of the ring are concave scallops 2, and in these scallops 2, are the raised ornaments 3. 20

I claim—

The design for a metal ring substantially as set forth and represented.

Signed by me this 22d day of June, 1894.

F. ECAUBERT.
